(57) CLAIM

The ornamental design for a storage cabinet, as shown and described.

DESCRIPTION

FIG. 1 is a front, right, top perspective view of the first embodiment of a storage cabinet, showing my new design; FIG. 2 is a rear, left, bottom perspective view thereof; FIG. 3 is a front elevational view thereof; FIG. 4 is a rear elevational view thereof; FIG. 5 is a left side view thereof; FIG. 6 is a right side view thereof; FIG. 7 is a top plan view thereof; FIG. 8 is a bottom plan view thereof; FIG. 9 is an enlarged view of detail 9 in FIG. 1; FIG. 10 is an enlarged view of detail 10 in FIG. 1; FIG. 11 is an enlarged view of detail 11 in FIG. 7; FIG. 12 is an enlarged view of detail 12 in FIG. 8; FIG. 13 is a front, right, top perspective view of the second embodiment of a storage cabinet, showing my new design; FIG. 14 is a rear, left, bottom perspective view thereof; FIG. 15 is a front elevational view thereof; FIG. 16 is a rear elevational view thereof; FIG. 17 is a left side view thereof; FIG. 18 is a right side view thereof; FIG. 19 is a top plan view thereof; FIG. 20 is a bottom plan view thereof; FIG. 21 is an enlarged view of detail 21 in FIG. 13; FIG. 22 is an enlarged view of detail 22 in FIG. 13; FIG. 23 is an enlarged view of detail 23 in FIG. 19; and, FIG. 24 is an enlarged view of detail 24 in FIG. 20. The dashed broken lines in the figures are for the purposes of illustrating portions of the storage cabinet and form no part of the claimed design. The dash-dot-dash broken lines are for notating enlarged views and form no part of the claimed design.
